(57) **CLAIM**

The ornamental design for a vehicle exterior, as shown and described.

DESCRIPTION

FIG. 1 is a front and left side perspective view of the vehicle exterior showing our new design;

FIG. 2 is a left side elevation view thereof, wherein the opposing right side elevation view is a mirror image thereto;

FIG. 3 is a top plan view thereof; and,

FIG. 4 is a front elevation view thereof, wherein the rear elevation view is a mirror image thereto.

The broken lines in the drawings illustrate portions of the vehicle exterior that forms no part of the claimed design. Furthermore, the vehicle exterior is shown with a symbolic break in its length. The appearance of any portion of the article between the cutaway sinuous broken lines forms no part of the claimed design.

1 Claim, 4 Drawing Sheets
